UNITED STATES PATENT OFFICE.

CHARLES H. GAGE, OF WASHINGTON, DISTRICT OF COLUMBIA, ASSIGNOR, BY DIRECT AND MESNE ASSIGNMENTS, TO LINN W. SEARLES, OF CHEVY CHASE, MARYLAND; WILLIAM A. FAISON, OF CHESTER, PENNSYLVANIA; AND WILLIAM D. RITER, OF WASHINGTON, DISTRICT OF COLUMBIA, TRUSTEES.

MINE-CAR COUPLER.

Application filed July 24, 1925. Serial No. 45,926.

This invention relates to a coupler for mine cars, the bodies of which dump sidewise, the general object of the invention being to provide means for connecting the coupler head 5 with the draw bar so that the head will remain in a horizontal position during the dumping action of the body and thus not strain the coupling parts nor act to uncouple them.

10 Another object of the invention is to provide a member which is pivoted to the head and which has a socket for receiving a ball on the draw bar so that the member and the head are swiveled on the draw bar.

15 This invention also consists in certain other features of construction and in the combination and arrangement of the several parts, to be hereinafter fully described, illustrated in the accompanying drawings and 20 specifically pointed out in the appended claims.

In describing my invention in detail, reference will be had to the accompanying drawings wherein like characters denote like 25 or corresponding parts throughout the several views, and in which:—

Figure 1 is an end view of a mine car showing my improved coupler in use.

Figure 2 is a similar view but showing the 30 body of the car in dumping position.

Figure 3 is a plan view with parts in section of the draw bar and coupler and portions of the supporting means for the draw bar.

35 Figure 4 is a side view of the draw bar and coupler, with parts in section.

Figure 5 is a view of the parts forming the swivel connection.

In these views, 1 indicates the truck of a 40 mine car and 2 the body thereof which is so connected with the trucks that it can rotate about a horizontal axis so that the body can be dumped sidewise, as shown in Figure 2. The draw bar 3 is carried by a frame 4 which is arranged in a yoke frame 5 attached to each end of the car body at the bottom thereof. The draw bar 3 passes through the bushings 6, the front one of 45 which is slidably supported in the frame and a spring 7 is placed between the bushings and acts to absorb the shocks of the two coupling heads coming together. Lateral movement of the coupling parts is re-

sisted by the coiled springs 8 which connect the bushings 6 with the sides of the frame 5. 55 These parts are all of well known construction and will not be described further.

The coupling head 9 has a socket 10 therein to receive the rounded end of a member 11 which is pivoted in the socket by the 60 pin 12. This member 11 is provided with a socket 13 to receive the ball 14 which is connected by the neck 15 at the outer end of the draw bar 3 so that the member 11 is swiveled to the draw bar, thus permitting 65 the coupler head 9 to remain in horizontal position, under the action of the weight 16 which is attached to the under face of the head, while the body of the car is in tilted 70 position, as shown in Figure 2. The member 11 is fastened to the ball by a pin 17 which passes through the holes 18 in the member and under the neck of the ball. The socket is formed with a rounded part to receive the ball and a straight part to receive 75 the neck.

From the foregoing, it will be seen that I have provided means for enabling the coupling means to remain in a horizontal position during the dumping action of the body 80 of the car so that there is no strain placed on the coupling parts nor is there danger of the parts uncoupling during the dumping action. Furthermore, it is not necessary to uncouple the cars in order to enable the cars 85 to dump. Figures 1 and 2 show that the draw bars are in alignment with the pivotal points of the body with the trucks.

It is thought from the foregoing description that the advantages and novel features 90 of my invention will be readily apparent.

I desire it to be understood that I may make changes in the construction and in the combination and arrangement of the several parts, provided that such changes fall within 95 the scope of the appended claims.

What I claim is:—

1. In a mine car, a draw bar and a coupling head, means for pivotally connecting the head with the bar so that the head can 100 rotate about a horizontal axis and a weight depending from the head for holding the same in a horizontal position when the draw bar turns with the dumping movement of the car body.
2. In a mine car, a member having a 105

socket therein, a ball on the draw bar engaging the socket so that the member can rotate about a horizontal axis and means for pivoting the coupling head to the member so that the head can rock about a vertical axis.

3. In a mine car, a draw bar having a neck at its outer end, a spherical member connected with the neck, a member having 10 a socket therein for receiving the neck and

spherical member, a pin passing through the socket member under the neck at a point where the neck joins the spherical member and its neck, said socket member having rotary movement on the spherical member and its neck and a coupling head pivoted to the socket member so that it can rock about a vertical axis. 15

In testimony whereof I affix my signature.

CHARLES H. GAGE.
